Primary Examiner — T. Chase Nelson*Assistant Examiner* — Eric Goodman*(74) Attorney, Agent, or Firm* — Volpe and Koenig, P.C.(57) **CLAIM**

The ornamental design for a faucet stream former, as shown and described.

DESCRIPTION

FIG. 1 is a top, front perspective view of the faucet stream former in accordance with my design;

FIG. 2 is a bottom, front perspective view thereof;

FIG. 3 is a left side elevational view thereof, with the right side elevational view being a mirror image thereof;

FIG. 4 is a front elevational view thereof, with the rear elevational view being a mirror image thereof;

FIG. 5 is a top plan view thereof; and,

FIG. 6 is a bottom view thereof.

The broken lines form no part of the claimed design.
